DESIGN FOR A SHOE OR SIMILAR ARTICLE

Vilem Forschner, New York, N. Y.

Application February 26, 1942, Serial No. 105,991

Term of patent 7 years

To all whom it may concern:

Be it known that I, Vilem Forschner, citizen of Czechoslovakia and residing at New York, N. Y., United States of America, have invented a new, original, and ornamental Design for a Shoe or Similar Article, of which the following is a specification, reference being had to the accompanying drawing, forming part thereof.

The figure is a perspective view of a shoe, showing my new design, the opposite side bearing substantially the same appearance as the side shown.

The essential features of my design reside in the parts shown in full lines.

I claim:

The ornamental design for a shoe or similar article, substantially as shown and described.

VILEM FORSCHNER.
